UNITED STATES PATENT OFFICE.

JOHN MARCHLENSKI, OF WHEELING, WEST VIRGINIA.

SHELVING-RACK.

1,303,094.

Specification of Letters Patent.

Patented May 6, 1919.

Application filed December 2, 1918. Serial No. 264,893.

To all whom it may concern:

Be it known that I, JOHN MARCHLENSKI, a citizen of the United States of America, and resident of Wheeling, county of Ohio, 5 and State of West Virginia, have invented certain new and useful Improvements in Shelving-Racks, of which the following is a specification.

This invention relates broadly to store 10 furniture, and more specifically to a shelving rack.

The primary object of the invention is to provide a portable shelf-carrying display rack designed particularly for use as a "cake 15 rack" for stores, and which may be employed in any place where shelf room is required.

A further object is to provide a rack of the character mentioned which, when not in use, may be folded to occupy relatively small 20 space, as for storage purposes.

With these and other objects in view, the invention resides in the features of construction, arrangement of parts and combinations of elements which will hereinafter be 25 specifically described, reference being had to the accompanying drawings, in which—

Figure 1 is a front elevation of the invention in which the parts are shown occupying their normal extended positions;

Fig. 2 is a vertical section on line 2—2, Fig. 1;

Fig. 3 is a front elevation of the invention, folded;

Fig. 4 is a top plan view of a removable 35 shelf;

Fig. 5 is an enlarged perspective view of a shelf-supporting cross-head; and—

Fig. 6 is a detail perspective view of the 40 joint provided at the upper ends of the standards of the frame.

Referring to said drawings, in which like designating characters distinguish like parts throughout the several views—

1 and 2 indicate, respectively, the front 45 and rear upright standards of a frame member of which there are two located at a suitable distance apart. The standards 1 and 2 of each frame member are rigidly connected by a plurality of cross-heads 3 which are 50 relatively spaced to correspond with the spacing desired for the shelves to be sustained thereby. Said cross-heads may be mounted in any appropriate manner, but, except the topmost crosshead 3^a, preferably 55 have end tenons 4 set in mortises provided therefor in said standards, as shown. The

said topmost crosshead 3^a has its ends mortised for the reception of tenons 5 formed on the upper ends of the standards, as is most clearly shown in Fig. 6.

Each of the cross-heads 3 has its inner edge projecting laterally from between the standards 1 and 2 by which it is carried. A projecting seating-ledge 6 is formed on said lateral edge for the reception of an end of a removable main shelf 7 which extends horizontally between the frame members. Said ledge 6 is formed by rabbeting the inner upper face of the cross-head to a depth corresponding with the thickness of the end of the shelf 7 which is to rest thereon.

Attached to the lowermost cross-heads 3 by means of hinges 8 is a horizontal upwardly-foldable brace member 9 which constitutes a part of the frame and which serves to normally maintain the lower ends of the opposite upright frame members rigidly in extended relation. A second brace-member 10 similar to said member 9 has the topmost shelf 7^a rigidly mounted thereon. The opposite ends of said shelf 7^a are hinged to the topmost cross-heads 3^a, as shown at 11. Each of said braces 9 and 10 is composed of two sections of equal length connected at their abutting ends by hinges 12 which permit of the upward folding of said sections to approximately the positions shown in Fig. 3.

Said shelves 7 seat loosely upon the ledges 6 with short end-tongues 13 formed thereon projected slightly within and closely fitting the space between the standards 1 and 2 whereby lateral displacement of said shelves is prevented. As is obvious, the various shelves 7 must be removed before folding of the braces 9 and 10 can occur.

Attached to each of said cross-heads 3 and 3^a at the outer lateral edge of the latter by means of hinges 14 are the inner ends of upwardly folding end-shelves 15 each of which has its outer end attached by hinges 16 to an upright end wall 17. In the normal lowered, or horizontal, position of said end shelves the lowermost thereof rests upon the top of a laterally extending bracket 18 which is rigidly carried by the opposite frame members, being mounted upon or against the lowest cross-head 3 and a caster-supported base 19, the latter constituting a mounting for the standards, as shown. When not in use the end-shelves 15 and end wall 17 may 110 together be elevated to the inclined folded position illustrated in Fig. 3, thus providing

for a considerable economy in space. While the end-shelves are herein shown as of relatively short length, it is evident that the same may be of any greater or lesser length 5 desired.

A bar 20 composed of two folding sections hinged together, as at 21, may be provided as a finishing rail, as shown in Figs. 1 and 2, the same having its ends hinged upon supporting posts 22 mounted upon the upper portions of the standards 2. When the bar 20 is employed, end rails 23 may also be hinged at their inner ends to said posts. As is obvious, said rails 20 and 23 are upwardly foldable so that folding of the rack parts hereinbefore described will in no way be interfered with.

The rack herein described is especially adapted for the reception of the cake and cracker containers or boxes commonly employed in retail groceries and bake shops, but may manifestly be used for displaying various other goods. When the device is used as a rack for cake boxes, a plate 24 is preferably pivoted adjacent to one of its ends on the under side of one of the shelves 7, the same normally occupying a position in closely underlying relation to said shelf, as shown in Figs. 1 and 2, and being adapted to be swung outward to occupy the dotted-line position shown in Fig. 4. In its outwardly swung, or extended, position said plate may be employed as a support for a box withdrawn from the rack while 35 contents are being removed from the box.

It will be understood that the foregoing description and the drawings have reference to what may be considered the preferred form of my invention. I reserve the right to make such changes or modifications in the form and arrangement of parts as may prove expedient and properly fall within the scope of the appended claims.

What is claimed is—

45 1. A folding shelving rack comprising upright supports, shelves demountably supported between said supports, upper and lower horizontal brace members having hinged connection at opposite ends with said supports, said members being composed of hinged sections which are foldable upwardly to permit said supports to approach each other, end shelves hinged at their inner ends to said supports, an end wall having hinged connection with the outer ends of said end shelves and supported by the latter, said end shelves and said end wall being foldable upward and inward toward the adjacent support.

60 2. A folding shelving rack comprising upright supports, shelves demountably supported between said supports, upper and lower horizontal brace members having hinged connection at opposite ends with 65 said supports, said members being composed

of hinged sections which are foldable upwardly to permit said supports to approach each other, end shelves hinged at their inner ends to said supports, an end wall having hinged connection with the outer ends of said end shelves and supported by the latter, said end shelves and said end wall being foldable upward and inward toward the adjacent support, and means for supporting said end shelves in horizontal position. 75

3. A folding shelving rack comprising upright supports, shelves demountably supported between said supports, upper and lower horizontal brace members having hinged connection at opposite ends with said supports, said members being composed of hinged sections which are foldable upwardly to permit said supports to approach each other, end shelves hinged at their inner ends to said supports, an end wall having hinged connection with the outer ends of said end shelves and supported by the latter, said end shelves and said end wall being foldable upward and inward toward the adjacent support, and brackets carried by said support and underlying the lowermost of said end shelves when the latter occupy horizontal position for supporting said end shelves and said end wall. 80

4. A folding shelving rack comprising two opposite frame members, each of said members including front and rear upright standards, cross-heads rigidly connecting the standards of each frame member, shelves interposed between said frame members and having their ends removably seated upon said cross-heads, sectional brace members having hinged connection at opposite ends with said frame members, the sections of said brace members being hinged together to permit upward folding thereof, end shelves having hinged connection with said frame members, and an upright member having hinged connection with each set of end shelves. 90

5. A folding shelving rack comprising two opposite frame members, each of said members including front and rear upright standards, cross-heads rigidly connecting the standards of each frame member, said cross-heads having inwardly projecting ledges, shelves interposed between said frame members and having their ends removably seated upon said ledges, sectional brace members having hinged connection at 110 opposite ends with said frame members, the sections of said brace members being hinged together to permit upward folding thereof, end shelves having hinged connection with said frame members, and an upright member having hinged connection with each set of end shelves. 115

6. A folding shelving rack comprising two opposite frame members, each of said members including front and rear upright 120

standards, cross-heads rigidly connecting the standards of each frame member, said cross-heads having inwardly projecting ledges, shelves interposed between said frame members and having their ends removably seated upon said ledges, said shelf ends having short tongues which fit between the standards of each frame member, sectional brace members having hinged connection at opposite ends with said frame members, the sections of said brace members being hinged together to permit upward folding thereof, end shelves having hinged connection with said frame members, and an upright member having hinged connection with each set of end shelves. 15

In testimony whereof, I affix my signature in presence of two subscribing witnesses.

JOHN MARCHLENSKI.
